UNITED STATES PATENT OFFICE.

ADOLPH WUNDER, OF NEW HAVEN, CONNECTICUT, ASSIGNOR TO SARGENT & CO., OF SAME PLACE.

DESIGN FOR A FIRE-DOG.

Specification forming part of Design No. 5,351, dated November 7, 1871.

To all whom it may concern:

Be it known that I, ADOLPH WUNDER, of New Haven, in the county of New Haven and State of Connecticut, have invented a new Design for Fire-Dog; and I do hereby declare the following, when taken in connection with the accompanying drawing and the letters of reference marked thereon, to be a full, clear, and exact description of the same, and which said drawing constitutes part of this specification, and represents a front view.

My invention relates to a design for fire-dog; and consists in the peculiar configuration, as shown in the accompanying drawing.

The standard rises from two feet which form the base, (the bar attached to the front at A,) thence running up contracting toward the top. B B are open spaces, the outline being irregular and as shown in the accompanying drawing. The surface is paneled and ornamented as shown, but this ornamentation is no part of my design, that consisting of the shape or configuration.

I claim as my invention—

The design for fire-dog, as described and shown in the accompanying illustration.

Witnesses: ADOLPH WUNDER.

A. J. TIBBITS,
JOHN H. SHUMWAY.
